HAND OPERATED CIGARETTE MAKING
MACHINE

Earl W. Brunton, St. Louis, Mo., assignor of one-half to Martin L. Medart, St. Louis, Mo.

Application September 19, 1931, Serial No. 563,781

10 Claims. (Cl. 131—5)

This invention relates to improvements in a hand operated cigarette making machine and has for its primary object to provide a machine which is simple and efficient in its operation.

- 5 Another object of the invention is to provide the machine with an endless apron by which the tobacco for each cigarette is molded and subsequently secured and wrapped within a required cigarette paper.
- 10 A further object of the invention is in providing a machine having an endless apron and a pair of cooperating rollers and means cooperable with one of the rollers whereby the apron can be positioned for receiving a quantity of tobacco and subsequently positioned for molding the tobacco in cigarette form for securing the paper wrapper thereon and for further positioning the said roller for discharging the cigarette.

A still further object of the invention is in providing the machine with means for holding the apron in position for receiving the tobacco preparatory to making a cigarette.

Other and further objects will appear in the specification and be specifically pointed out in the appended claims, reference being had to the accompanying drawing, exemplifying the invention, and in which:—

Figure 1 is a side elevation of this improved cigarette making machine.

30 Figure 2 is a plan view of Fig. 1.

Figure 3 is a view of a fragmentary portion of the machine showing the mechanisms in position for forming or molding the cigarette.

35 Figure 4 is a fragmentary view similar to Fig. 3 but showing the mechanisms in a further operated position for discharging a cigarette after being made.

Referring by numerals to the accompanying drawing, 1 designates an open top receptacle having end walls 2, side walls 3 and a bottom 4 and disposed transversely in said receptacle and supported in the side walls 3 is a shaft 5, said shaft having protruding ends and mounted on each protruding end of said shaft are respective legs 6 of an inverted U-shaped member 7 which is in the form of a lever.

40 Intermediately formed on each leg 6 is an ear 8 having a slot 9 and mounted in each slot is the shaft end 10 of a horizontally disposed roller 11 and engaged in each leg 6 adjacent the ears 8 is a shaft end 12 of a friction driving roller 13, said roller 13 paralleling the roller 11.

45 Swingly engaged on each shaft end 12 of the roller 13 is a leg 14 of a U-shaped securing member 15, the cross portion 16 being adapted to en-

gage in the recesses 17, one of which is formed in the upper edge of each of the side walls 3 of the receptacle. Securely fixed on one of the shaft ends 12 of the roller 13 is a turning handle 18 and secured to each leg 6 of the lever 7 is a retractile coil spring 19, each of said springs at their opposite ends being secured to respective side walls 3 of the receptacle 1.

50 Supported on each side wall 3 of the receptacle adjacent the top thereof is a shaft end 20 of a roller 21 which is parallelly disposed to the roller 11 and mounted over said rollers 21 and 11 is an endless apron 22 and disposed in the receptacle 1 between the side walls 3 thereof is a partition 23 which is inclined from one side of the roller 20 60 downwardly to the adjacent end wall 2 thereby forming a receiving pocket 24 in the receptacle.

55 In the operation of this improved machine for making cigarettes, cigarette tobacco may be placed in the receptacle 1 so as to be convenient to the operator and the lever 7 is swung on the shaft 5 to the position shown in Fig. 1 and may be held in this position by the securing member 15 having the cross portion 16 thereof engaged in the recesses 17. In this held position of the lever 7, the roller 11 is parted at a considerable distance from the fixed roller 21 by reason of the roller 11 being carried by the lever 7. This parted position of the rollers 11 and 21 provides ingress to the pocket A formed by the loosely depending apron 22 so that a quantity of tobacco can be placed in the pocket A.

60 After a desired quantity of tobacco has been inserted in the pocket A, the securing member 15 is released from the recesses 17 and the lever 7 is acted on by the springs 19 and the roller 11 is thus moved to a position adjacent the roller 21 as shown in Fig. 3 and in which the shaft ends 10 of said roller 11 will rest in respective notches 25, one of which is formed in the upper 70 edge of each side wall 3.

65 As the shaft ends 10 of the roller 11 engage and rest in the notches 25, the slots 9 in the lever 7 permit further movement of the lever 7 so that the friction roller 13 will be brought into contact with the apron on the roller 11. In this position and as shown in Fig. 3, when the handle 18 is turned in a right hand direction, the friction roller 13 will cause the apron 22 to be fed between it and the roller 11 thereby travelling the apron and the roller 21 and the tobacco in the pocket A 80 will be revolved into a neatly formed roll.

70 After the tobacco in the pocket A has been formed into a roll by a few turns of the handle 18, a cigarette wrapping paper B preferably having a damped gummed edge is then inserted in the 85

90

100

105

110

narrow gap between the rollers 11 and 21 as shown in Fig. 3 and further turning of the handle 18 will feed the cigarette paper B around the rolled tobacco and the pressure of the travelling apron 5 thereagainst will seal the gummed edge.

Obviously, the firmly securing of the paper wrapper around the tobacco roll is quickly done and the lever 7 is then engaged and pressed downwardly thereby parting the rollers 11 and 21 to a position in which the apron 22 will become approximately taut thus quickly elevating the cigarette from its pocketed position and by reason of the roller 11 being disposed on a plane above the roller 21, when the lever 7 is downwardly pressed 10 as shown in Fig. 4, the cigarette will be discharged down the inclined partition 23 into the pocket 24.

In operating the lever 7 for discharging the cigarette after it has been made, it will be necessary for the operator to elevate the lever 15 so 20 that it will override the recesses 17 in the side walls 3.

Attention is further directed to the slots 9 formed in the ears 8 of the lever 7 which permits play or looseness of the shaft 10 of the roller 11, 25 said slots permitting the roller 11 to be forced somewhat to one side while engaging the tobacco in the pocket A when the lever 7 is in the positions shown in Figs. 1 and 2 and further, in the event that a greater quantity of tobacco is 30 placed in the pocket than is ordinarily placed therein, the slots 9 will permit a certain amount of yield to the roller 11 for accommodating the larger quantity of tobacco in the pocket A of the apron 22. Also, the movement permitted the 35 shaft 10 of the roller 11 in the slots 9, permits the operator to regulate the tension on the apron 22 and the roller 11 for providing a smooth feeding-in-action on the cigarette paper B.

The roller 13 is preferably made of rubber or 40 other analogous material and if desired all of the rollers 11, 13 and 21 may be made of rubber or rubber coating for better frictional engagement with the apron 22.

In order to prevent portions of tobacco projecting from one end of the cigarette which may be termed the mouth end, a cylindrical plug shown at C in Figs. 2 and 3 may be inserted in one end of the apron pocket A for abutting one end of the tobacco quantity when tobacco is placed in the 45 pocket and consequently when a cigarette paper B is fed around the tobacco roll in the pocket, one edge of the paper will overengage the plug and obviously when the cigarette is discharged from the machine a countersunk or depression will be 50 found to be formed in one end thus preventing the tobacco ends from protruding from this particular end of the cigarette.

While one illustrative embodiment of the invention has been described in detail, it is not my 60 intention to limit its scope to that particular embodiment or otherwise than by the terms of the appended claims.

What I claim is:—

1. A cigarette making machine comprising a 65 lever, a roller carried by said lever, a second roller having a fixed mounting, an apron mounted over said rollers, and travelling means for said apron carried by said lever adjacent said first mentioned roller.

70

2. A cigarette making machine comprising a lever, a roller carried by said lever, a second roller having a fixed mounting, an apron mounted over said rollers, said lever when operated adapted to flex said apron for providing a tobacco receiving pocket therein, and means carried by said lever adjacent said first mentioned roller for travelling said apron in its pocket formed position. 80

3. A cigarette making machine comprising a lever, a roller carried by said lever, a turning element carried by said lever beyond the pivot thereof for operating said roller, a second roller having a fixed mounting, and an apron mounted over said rollers, said lever adapted to be moved and cause said apron to flex for providing a tobacco receiving pocket thereon. 85

4. A cigarette making machine comprising a lever, a roller carried by said lever, a turning element carried by said lever adjacent said roller for operating said roller, a second roller having a fixed mounting, and an apron mounted over said rollers, said lever adapted to be actuated to cause said apron to flex for providing a tobacco receiving pocket thereon, and said lever being adapted to be operated to cause said apron to discharge 90 the made cigarette therefrom.

5. A cigarette making machine comprising a pair of rollers, an apron mounted over said rollers, one of said rollers being movable and resiliently held relative to said other roller for flexing said 100 apron to provide a larger or smaller tobacco receiving pocket therein, and driving means for said apron cooperable with said resiliently held roller.

6. A cigarette making machine comprising a pair of rollers, an apron mounted over said rollers, 110 one of said rollers having a mounting for permitting sliding of the roller axis therein, a lever for the support of said slidable roller, and means for travelling said apron carried by said lever.

7. A cigarette making machine comprising a 115 pair of rollers one of which is fixed and the other of which is movable, a lever for the support of said movable roller, an apron mounted over said rollers, and a driving roller carried by said lever cooperable with said apron and said movable 120 roller.

8. A cigarette making machine comprising a fixed roller, a lever, a pair of rollers carried by 125 said lever one of which is provided with a slidable axis, and an apron mounted over said first mentioned roller and said roller having the slidable axis.

9. A cigarette making machine comprising a lever, a roller carried by said lever, a second roller having a fixed mounting, an apron mounted over 130 said rollers, travelling means for said apron carried by said lever, and releasable means for holding said lever in retractile position.

10. A cigarette making machine comprising a frame, a lever pivoted to said frame, a roller carried by said lever, a second roller having a fixed mounting, an apron mounted over said rollers, travelling means for said apron carried by said lever, and means cooperable with said lever and said frame for holding said lever in a retracted 135 position. 140
